(57) **CLAIM**

The ornamental design for a laryngoscope blade, as shown and described.

DESCRIPTION

The file of this patent contains at least one drawing/photograph executed in color. Copies of this patent with color drawings will be provided by the Office upon request and payment of the necessary fee.

FIG. 1 is a side view of a laryngoscope blade showing my new design;

FIG. 2 is a bottom perspective view thereof;

FIG. 3 is a top perspective view thereof;

FIG. 4 is a side view thereof;

FIG. 5 is a further top view thereof;

FIG. 6 is an end perspective view thereof;

FIG. 7 is a further top perspective view thereof; and,

FIG. 8 is a further side perspective view thereof.

The two dimensional surface treatment visible in FIGS. 3, 4 and 7 shows the part number MIL 2, and this designation forms no part of the ornamental design of the present invention.
